No. 36,767.

Patented February 2, 1904.

UNITED STATES PATENT OFFICE.

LEOPOLD JACOBI, OF ST. LOUIS, MISSOURI, ASSIGNOR TO NATIONAL CASH REGISTER COMPANY, OF JERSEY CITY, NEW JERSEY, A CORPORATION OF NEW JERSEY.

DESIGN FOR A CASH-REGISTER CABINET OR CASING.

SPECIFICATION forming part of Design No. 36,767, dated February 2, 1904.

Application filed October 14, 1903. Serial No. 177,078. Term of patent 7 years.

To all whom it may concern:

Be it known that I, LEOPOLD JACOBI, a citizen of the United States, residing at St. Louis, in the State of Missouri, have invented a new, 5 original, and ornamental Design for Cash-Register Cabinets or Casings.

The accompanying drawing, forming part of this specification, shows a three-quarter's front perspective view of a cash-register cabinet or casing having the design of my present invention.

What I claim is—

The ornamental design for a cash-register cabinet or casing as shown.

In testimony whereof I affix my signature in 15 the presence of two witnesses.

LEOPOLD JACOBI.
